CLAIM

The ornamental design for a power station for personal electronic devices, as shown and described.

DESCRIPTION

FIG. 1 is a perspective view of a power station showing the top, front, and right sides of my new design;

FIG. 2 is a second perspective view, showing the top, rear, and right sides thereof;

FIG. 3 is a front side view thereof;

FIG. 4 is a rear side view thereof;

FIG. 5 is a left side view thereof;

FIG. 6 is a right side view thereof; and,

FIG. 7 is a top plan view thereof.

The characteristic feature of the ornamental design resides in the use of metallic surface material on portions of the power station. The metallic surface is illustrated in FIGS. 1-7 through the use of oblique line shading. Metallic surfaces may include such materials as chrome-plating, stainless steel, brass, gold, platinum, silver, etc. Surfaces not specified as metallic are illustrated in FIGS. 1-7 through the use of stippling.
